UNITED STATES PATENT OFFICE.

JESSE DITSON, OF LITTLETON, COLORADO, ASSIGNOR TO INGERSOLL-RAND COMPANY, OF JERSEY CITY, NEW JERSEY, A CORPORATION OF NEW JERSEY.

DOLLY-RETURN DEVICE.

1,386,769.

Specification of Letters Patent. Patented Aug. 9, 1921.

Application filed September 22, 1920. Serial No. 412,048.

To all whom it may concern:

Be it known that I, JESSE DITSON, a citizen of the United States, residing at Littleton, Arapahoe county, Colorado, have invented certain new and useful Improvements in Dolly-Return Devices, of which the following is a specification.

This invention relates to an automatic return for a fluid actuated dolly, such as used 10 for instance in sharpening drill steels. The dolly is adapted to receive the impact blows of a piston hammer in a cylinder, and difficulty is experienced in preventing the 15 springs or other devices for returning or re-tracting the dollies from breaking under the severe usage to which they are subjected.

The primary object of the present invention is to lessen the breakage of the springs or other return devices, and secure a simple, 20 compact and strong return device yieldably controlled and actuated by fluid pressure.

To these ends the invention is illustrated in one of its preferred forms in the accompanying drawings, in which—

25 Figure 1 is a longitudinal sectional elevation of a return device and so much of a dolly operating cylinder as will serve to illustrate the invention taken on the line 2—2 of Fig. 2, and

30 Fig. 2 is an end view of the apparatus.

Referring to the drawings, A represents a portion of a cylinder having a fluid actuated piston hammer B therein for imparting impact blows to the dolly C carried in the 35 front head D secured to the cylinder as by means of the usual side bolts E. Any suitable means (not shown) may be provided for supplying fluid pressure to the cylinder A for actuating the piston hammer B.

40 In order to provide a suitable and convenient mounting for the dolly return device, I have shown a bracket F secured to the lower portion of the cylinder A as by means of the bolts G and this frame is provided with suitable lugs H through which a pivot pin J extends secured in position as by means of the cotter pin K and forming a pivot for the dolly return member which in this instance is preferably in the form of 45 a bent spring L having coils O encircling the pivot pin J and provided with an arm or arms P engaging the slot Q in the dolly.

The other end of the spring is bent at an angle to the arms P to form an actuating arm R by means of which the dolly return member may be retracted.

Instead of supporting the arm R rigidly against a stop, I have provided a fluid actuated device co-operating with said arm for yieldably resisting the movement of the 60 spring member P and in this instance the fluid operated device consists of a plunger S movable within the fluid pressure chamber T and adapted to bear against the actuating arm R of the member L. Fluid pressure may be supplied to the chamber T from the inlet passage U adapted to connect with the supply of the cylinder A, and a supply passage V in the cylinder connects with a supply passage W in the bracket F and 65 leads to the port X in the chamber T.

In the operation of the device, the plunger S is maintained under fluid pressure in the chamber T while the piston hammer B is operating to impart blows to the dolly C, 75 and each time that the dolly is driven forward, it will be automatically returned by the spring member L due to the resiliency of the spring and the pressure exerted by the plunger S on the actuating arm R of 80 the spring. The liability of breakage is eliminated, or at least greatly reduced, because the resiliency of the spring is not alone depended upon to return the dolly, but the spring is assisted by the fluid actuated plunger S.

I claim:

1. An automatic return device for a fluid actuated dolly, comprising a resilient member, pivoted adjacent the dolly and engaging 90 the dolly, and fluid actuated means co-operating with said member for retracting the dolly.

2. An automatic return device for a fluid actuated dolly, comprising a resilient member pivoted adjacent the dolly and having one arm engaging the dolly and another actuating arm extending at an angle to said first arm, and a fluid operated plunger adapted to bear upon said actuating arm 100 and yieldingly resist the outward movement of the dolly.

3. An automatic return device for a fluid actuated dolly, comprising a spring bent into

the form of a bell crank and pivoted adjacent the dolly, one arm of the spring engaging the dolly, and a fluid operated plunger adapted to press against the other arm of 5 the spring for retracting the dolly.

4. An automatic return device for a fluid actuated dolly, comprising a spring member pivoted at one side of the dolly, one arm of said member engaging the dolly, another 10 actuating arm extending at one angle to the said dolly engaging arm, and fluid operated means coöperating with said actuating arm

for rocking the spring member on its pivot to return the dolly to initial position.

5. An automatic return device for a fluid 15 actuated dolly, comprising a member pivoted adjacent the dolly and having one arm engaging the dolly and another actuating arm extending at an angle to said first arm, and fluid operated means coöperating with 20 said actuating arm for retracting the dolly.

In testimony whereof I have signed this specification.

JESSE DITSON.
